FIG. 2

UNITED STATES PATENT OFFICE

2,268,631

PRINTING TELEGRAPH SYSTEM AND APPARATUS

Raymond E. Zenner, Chicago, Ill., assignor to Teletype Corporation, Chicago, Ill., a corporation of Delaware

Application May 23, 1938, Serial No. 209,523

19 Claims. (Cl. 178—4)

This invention pertains to printing telegraph systems and more particularly to telegraph systems and apparatus adapted to be operated intermittently under the control of records in a control strip.

In telegraph systems involving apparatus for recording characters by a series of elemental areas of positive and negative surfaces, transmitting apparatus has been employed wherein each letter, symbol, or character is analyzed into a succession of constituent areas and a code set of corresponding character embodiments are constructed, which embodiments then are selected under control of a message record tape. In accordance with such scanned or analyzed embodiments, electrical impulses are generated which cause corresponding operation of recording apparatus of the form disclosed in United States Patent No. 2,131,741 to form the characters in a line.

An important object of the present invention is to control automatically the cessation of transmission of signals from a tape controlled transmitting mechanism in response to a taut condition of the tape and to provide for resumption of transmission only in response to manual control.

Another object of the present invention is to provide an arrangement for invariably supplying to a transmission channel a start condition automatically upon a resumption of message transmission to assure that tape feeding will start in the printer when the transmitter is started and before message matter is transmitted.

In accordance with a feature of the invention a means is provided in an intermittently operating system for transmitting the start signal invariably when transmission is resumed after a cessation thereof to avoid the necessity as in synchronous systems of moving or feeding the receiving and recording tape continually.

A feature of the invention is directed to the tape control circuit for telegraph printers whereby the tape is caused to move continuously only during the time when messages are being recorded.

A further feature pertains to printing on waxed paper by arcing between the scanning wheel and a knife-edge platen.

Another feature of the invention pertains to means for assuring the distinct printing of characters by eliminating rebound of the printing hammer.

The above and other objects of the invention are achieved through the provision of a mechanism for sensing perforations in a tape perforated

in accordance with a five-unit or Baudot code which, through its electrical contacts, controls the energization of a plurality of electromagnets one individual to each element of the code. 5 These electromagnets serve to control latches individual to each of a plurality of permutation bars. The permutation bars are thus set, in accordance with the energization of the electromagnets and in accordance with the code combination appearing in the perforated tape, to select one pair of a plurality of pairs of brushes. Individual to each pair of brushes is a pair of code discs designed in accordance with a method of prescanning in which the characters or symbols to be transmitted are divided into any desirable number of sending units or areas. The several unit areas thus created are assigned in order of scanning to the periphery of the code discs. Specifically, the two discs constituting a 10 pair of code discs are allocated to letters and figures or upper and lower case characters, respectively. With the selection and cooperation of a pair of brushes with a pair of code discs, it is necessary to select between code discs of the pair. To accomplish such a result, mechanism responsive to shift and unshift signals appearing in the perforated tape is provided to select between a pair of collector rings, one identified with the shift signal and the other identified with the unshift signal. Under such circumstances, one disc of each of the pairs of discs will be connected to one of the collector rings, whereas the other disc of each of the pairs of discs will be 15 connected to the other collector ring and by selecting between the collector rings in accordance with the shift and unshift signal combinations, the individual disc indicative of the character to be transmitted can be selectively determined. Inasmuch as the code discs rotate, 20 continuously by power communicated thereto from a continuously rotating motor and the brushes are selectively operated in accordance with the permutative setting of the permutation bars, impulses representative of the positive and negative surfaces of the character code disc will be transmitted, which will be effective at the receiving end of the system to record a character in accordance with the pattern of the character formed on the periphery of the code disc then effective for the transmission of the characteristic impulses.

As previously indicated, the code discs rotate continuously, and further, the permutation bars are set in response to the energization of electromagnets controlled by a tape sensing mechanism

which receives its operating impulses from a cam rotated in timed relation with the rotation of the code discs. The cam, through contacts associated therewith, serves to control the operation of the tape sensing mechanism; that is, for each rotation of the code discs together with their cam, an electrical impulse is generated which causes the tape sensing mechanism to withdraw its tape sensing fingers and advance the tape to present the next transverse row of perforations in alignment with tape sensing elements of the sensing mechanism. Under certain conditions, it is desired to arrest the operation of the transmitter or the tape sensing mechanism and therefore mechanism is provided for locking the tape sensing elements in their withdrawn position, notwithstanding the fact that the control cam and the code discs continue to rotate. Such a result is accomplished through the provision of a contact operated by a taut-tape switch arm which, when opened, causes the de-energization of a relay of the circuit to establish a condition to energize a control relay which, in return, controls the energization of a locking magnet of the tape sensing mechanism to render it ineffective, notwithstanding the fact that the operating magnet of the tape sensing mechanism continues to be energized once for each cycle of rotation of the code discs and their associated control cams. When the operation of the transmitter is thus arrested, it causes the movement of the tape at the printer to be arrested by controlling the release of the tape stop magnet armature due to the presence of spacing current on the signal line.

Further control means is provided according to the present invention to insert automatically, upon restarting the transmitter by closing the contact operated by the taut-tape switch arm, a start signal which acts to operate the tape stop magnet, which, upon re-energization, acts to initiate the movement of the tape at the printer preparatory to resumption of message transmission and reception.

The invention will be explained hereinafter more fully with reference to the accompanying drawings, of which

Fig. 1 shows schematically the tape sensing mechanism and the elements of the distributor through which the electrical impulses indicative of the characters are transmitted;

Fig. 2 shows diagrammatically elements of the transmitter;

Fig. 3 is a schematic view of a receiver circuit embodying a tape stop control arrangement;

Figs. 4, 5 and 6 represent modified tape stop control arrangements;

Fig. 7 is a schematic view of a receiving circuit for printing on chemically prepared paper by means of arcing; and

Fig. 8 is an enlarged cross sectional view of the line coil and platen shown in Figs. 3 to 6.

Referring now to the drawings, particularly Fig. 2, it is noted that shaft 7 has secured thereto a pinion gear 8 which meshes with a worm gear 9 driven by power communicated from a continuously operating motor 10. The relation between gears 8 and 9 is such as to cause rotation of shaft 7 at a speed calculated to effect the accurate and proper distribution of current impulses indicative of the characters to be transmitted. Secured also to shaft 7 are a plurality of code signal discs 12, each forming a transmitting element, or character member, symbol or physical embodiment of a symbol. These code

signal discs, as best shown in the lower part of Fig. 1, are composed of a plurality of discs arranged in pairs; that is, a pair of code signal discs 12 constitute a unit, one disc of which corresponds to a lower case character, whereas the other disc corresponds to an upper case character.

Code signal discs 12 are designed according to a method of prescanning, in which characters or symbols to be transmitted are divided into any desirable number of sending units or areas, as fully described in the aforementioned patent. The several unit areas thus created are assigned in order of scanning to the periphery of each of the discs 12, the dark areas of a signal or message unit being the high surfaces 14 to engage a brush designed to cooperate therewith to send a signal. It is, of course, obvious that the depressed or reduced or insulated portions of the code discs 12 represent the light areas of the signal or message unit. Obviously the light areas might be made the high surfaces, depending upon the preferred method of transmission.

The term mechanical prescanning refers to the analysis of a character into the signals suitable for transmission and comparable to the scanning of the character. The production of the mechanical member or disc containing elements thereby corresponds directly and individually to the signals and represents individual characters. For example, a character or letter may be pre-scanned by dividing its total area into a plurality of unit areas arranged in a predetermined number of vertical strips with a predetermined number of units within each strip. The character is thus divided into a plurality of strips laid off in a predetermined number of equal angular sectors on the code signal disc 12 and each angular sector is divided into a predetermined number of angular units, each corresponding to a unit area of the corresponding vertical strip. The periphery of the code disc 12 is then executed by recessing the corresponding disc unit sections of each sector where the respective unit areas are light, and where the units are dark, raised surfaces 14 remain. With such a plan, each of the code discs 12 is correspondingly developed.

From the foregoing explanation of the arrangement of the code discs 12, it is evident that the present invention contemplates a code disc for each character or symbol to be transmitted; that is, there will be a code disc 12 individual to each letter of the alphabet and each numeral and other special characters. These code discs, being secured to but insulated from shaft 7, will rotate therewith continuously, and during their rotation, provided a selection has been established, will effect the transmission of signal impulses indicative of its character.

The discs 12 are arranged in pairs and being so arranged, it is necessary to interconnect a disc of each pair which, in turn, are connected to a collector ring 15 which is also secured to shaft 7. Likewise, the other code disc of each of the pairs of code discs are interconnected and, in turn, are connected to a collector ring 16 which, as noted for collector ring 15, is also secured to shaft 7. Interconnection of the several code discs with the collector rings 15 and 16, respectively, is achieved through the provision of coiled conductor springs 17 and 18. The coiled springs 17 and 18 are compressed between corresponding ones of the pairs of code discs 12 and are insulated from the intermediate code

discs by sleeve members 6 of insulating material. In addition to code discs 12 and collector rings 15 and 16, discs 19 and 28 are secured to shaft 7. The latter discs serve, in response to a predetermined signaling condition and through their cooperation with brushes individual thereto, to transmit a start signal at the beginning of each resumption of message transmission, as will be explained hereinafter.

In the operation of the transmitter certain functional operations are performed by cams 22, 23, and 25 secured to shaft 7. The noted cams are positioned on shaft 7 with respect to each other and with respect to code discs 12 to perform their respective functions in timed relation with the other functional responses and the transmission of signal impulses from the code discs 12. It is obvious, therefore, that the cams 22, 23, and 25 may be oriented on shaft 7 with respect to each other to provide proper sequential operation in a manner fully contemplated by the present invention.

Positioned below the shaft 7 and the code discs 12 are a plurality of permutation bars 27, 28, 29, 30, and 31, or one individual to each element of the code. According to the embodiment of the invention disclosed in the aforementioned drawings, a five-unit code is employed. Accordingly, there are five permutation bars or one individual to each element or unit of the code. Operation of the permutation bars is attained through the arrangement of an electromagnet individual to each of the bars. Under such circumstances there are five electromagnets 35, 36, 37, 38, and 39. These electromagnets are selectively controlled from a tape sensing mechanism 46 and each controls, through its armature, a spring-held latch 42 which engages a shoulder formed on the upper edge of its permutation bar to hold it against the action of its spring 43, there being a spring 43 individual to each of the permutation bars. Under such circumstances, when an electromagnet is energized, the spring loaded latch 42 is operated to move its end free of the projection on the upper edge of its permutation bar, whereupon such permutation bar is moved to the left, as viewed in Fig. 1, by the action of spring 43.

The tape sensing mechanism 40, as is fully and completely disclosed in U. S. Patent No. 1,460,357 embodies a plurality of tape sensing fingers 46 which serve to sense perforations in tape 50 which has been perforated through the operation of a keyboard perforator to form transverse rows of code perforations indicative of the characters or symbols of the message to be transmitted through the effectiveness of code discs 12. As is fully disclosed in said Patent No. 1,460,357, the sensing fingers 46 are pivoted on a rod 51 and are movable about such rod by an electromagnet 52. Specifically, electromagnet 52, upon being energized, draws its magnetic yoke to shift its cores axially to push a nonmagnetic pivoted plate 53 against the five tape sensing fingers 46 and thus withdraws the sensing fingers 46 from engagement with the perforations in the tape 50 and causes, following such withdrawal, the advancement of the tape through a ratchet and pawl mechanism (not shown) to present the next transverse row of perforations in alignment with the withdrawn ends of the sensing fingers 46.

Attached to and operated by each of the sensing fingers 46 is a contact spring 53. There being five sensing fingers 46, there are five con-

tact springs 53. Contact springs 53 cooperate with stationary contacts 54 to effect a circuit closure and cause the energization of the electromagnet connected thereto, since the contact springs 53 are connected through their individual springs 55 to a positive bus bar 56.

Assume, for example, that a sensing finger 46 encounters a perforated area in tape 50. Through its contact spring 53, engagement will be made with its stationary contact 54 and an energizing circuit for the electromagnet 35-39 connected thereto will be established. The electromagnet will be energized, and latch 42 will be operated against the action of its spring to free the permutation bar individual thereto for action by its spring 43. Such permutation bar will be moved to the left, as viewed in Fig. 1.

Under certain conditions of operation, it is desirable to prevent the operation of the tape sensing fingers 46, notwithstanding the fact that the electromagnet 52 is energized cyclically. In order to achieve such a result, an electromagnet 58 having an armature 59 is provided. Through its armature, electromagnet 58 locks the pivoted plate of electromagnet 52 so that, notwithstanding the fact that the electromagnet 52 is energized cyclically, it will have no functional response on the sensing fingers 46, its cores merely engaging the pivoted plate 57 held fixed by armature 59.

As shown in Fig. 1, the lower edge of each of the permutation bars 27-31 is formed with a plurality of notches arranged permutably so that upon the permuted operation of electromagnets 35-39, corresponding operation of the permutation bars 27-31 will result in the alignment of the notches to effect the selection of one of a plurality of selectable bars 63. There is a selectable bar 63 individual to each pair of code signal discs 12. Each selectable bar 63 is individual to a brush carrier or support 64 pivoted on rod 65. The brush supports 64 carry a pair of brushes 66 and 67 individual to respective code signal discs 12 constituting a pair of code signal discs.

Each of the brush supports 64 has a downwardly projecting portion 68 which lies in the path of its individual selectable bar 63, so that upon the operation of selectable bar 63, brush support 64 will be rotated in a clockwise direction about rod 65, as viewed in Fig. 2, against the action of its retractile spring 69 provided, however, that the brush support 64 is at that instant free to move. As shown in Fig. 2, the brush support 64 has an extension 70 arranged with its end formed in a knife-like fashion to cooperate with a correspondingly shaped bail 71 which is pivoted on rod 72 and which is operated by cam 22 against the tension of a spring 73 to free, through its disassociation with extension 70, brush support 64 for operation. Release of extension 70 of brush support 64, as will of course be recognized, occurs in timed relation with respect to the other functional responses of the apparatus.

Common to all selectable members 63 is a bail 76 which extends above and transversely of the selectable members 63. Bail 76 is formed on one end of a lever 77 which is pivoted at 78 and which carries at its other end a roller 79 which cooperates with cam 23. Cyclically with the rotation of shaft 7, cam 23 is effective for operating lever 77 to move selectable members 63 counterclockwise about their pivot 78 against the action of their retractile springs 69, there being a retractile spring 80 individual to each

of the selectable members 63. With the selectable members 63 moved counterclockwise, as viewed in Fig. 2, and out of engagement with permutation bars 27-31, the permutation bars are free to be moved under the control of electromagnets 35-39 in response to the operation of the tape sensing fingers 46.

When the permutation bars 27-31 are positioned in various combinations in response to the permuted energization of the electromagnets 35-39, a selectable member 63 will be rotated about rod 65 by its spring 80 to engage projection 68 of brush carrier 64, and since at that instant bail 71 has been moved free of extension 78 of brush support 64, the brush support 64 will be moved to cause the engagement of brushes 66 and 67 with their respective code discs 12. Under such conditions, some of the bars 27-31 may be to the left and others in their normal unactuated position. Following the setting of the brush support 64, the locking ball 71 is restored by its spring 73 to a position where it engages extension 78 and holds the brush support 64 in its set position. The selectable member 63 is thereupon free to be restored to its normal position out of cooperation with the permutation bars 27-31 and thus the permutation bars may be reset to select either the same selectable member 63 or another selectable member 63 identified with a different pair of characters. With such an arrangement it is possible to initiate a selection during the interval the brushes 66 and 67 are in engagement with the code disc 12 for the transmission of signal impulses characteristic of their peripheral formations. Such an arrangement has been referred to as an overlap, since it makes possible a selection during the period impulses are being transmitted for a previous character selection.

Following the selection of a selectable bar 63 and the operation of a brush support 64, a cam (not shown) becomes effective to restore any of the permutation bars 27-31, previously moved to the left as a result of the energization of the electromagnets 35-39, to a position where the latches 42 are effective to hold the permutation bars against the action of their springs 43. Cyclically, therefore, with respect to the rotation of shaft 7, the permutation bars 27-31 will be restored to their normal or unactuated position.

As previously described, a code disc 12 of each pair of code discs is connected to collector rings 15 and 16, respectively. Continuously in engagement with each of these rings is a brush 84 and 85 (Fig. 1), respectively. These brushes are connected through electrical conductors to contacts 86 and 87, respectively. Cooperating with these contacts is a contactor 88 pivoted at one end and engaged at its other end by a rockable member 89. Secured to member 89 are two oppositely arranged bell crank levers 90 and 91, arranged to move member 89 either to the right or left, depending upon whether bell crank lever 90 or bell crank lever 91 is operated to cause corresponding movement of contactor 88 to engage either contact 86 or contact 87.

Operation of bell crank levers 90 and 91 is achieved through selectable bars individual thereto. As shown in Fig. 1, selectable bar 93 is individual to bell crank lever 90, while selectable bar 94 is individual to bell crank lever 91. Upon the selection and operation of either of the selectable bars 93 or 94, the bell crank lever 90 or 91 individual thereto will be operated and corresponding movement of member 89 will be

effected. The selection and operation of the selectable bars 93 and 94, which are identified with figures and letters or shift and unshift signal combinations, respectively, are selected and operated through the setting of the permutation bars 27-31 in response to the energization of the electromagnets 35-39 for the signal combinations identified with figures and letters, respectively; that is, when a transverse row of perforations in tape 50 for figures is sensed by mechanism 48, the tape feelers 46 are operated correspondingly and the contact members 53 will be operated to cause the energization of certain of the electromagnets 35-39 to set permutation bars 27-31 to align their notches to select and permit the operation of selectable bar 93. Under such conditions of operation, member 89 will be moved to the right through the rotation of bell crank lever 90 in a counterclockwise direction to cause the engagement of contactor 88 with contact 87. Inasmuch as contactor 88 was previously in engagement with contact 86 and since the contacts 86 and 87 are connected to collector rings 15 and 16, respectively, the circuit will be changed from collector ring 15 to collector ring 16. Correspondingly, selectable bar 94 may be operated in response to a letters code combination in tape 50 to cause the member 89 to move contactor 88 from engagement with contact 87 to engagement with contact 86.

Inasmuch as a code disc of each pair of code discs is connected either to collector ring 15 or collector ring 16 and since the circuit from the collector rings 15 and 16 is determined by the position of contactor 88, the effective circuit will depend upon the position of contactor 88 which, as shown in Fig. 1, is connected to a radio frequency transmitter 95 which may be of any design. Of course, instead of employing a radio transmitter, operation of the system according to the present invention over land wire lines by direct current or carrier current signals is also feasible.

Positioned near the entrance end of the tape senser 40 is a mechanism commonly referred to as a taut-tape switch mechanism which responds to the tape to exercise control functions. Such a mechanism, as exemplified in Fig. 1, embodies a bracket 96 to which is pivoted an arm 97 extending transversely of and adapted to be engaged by the tape 50. Cooperating with arm 97 is a lever 98 which is also pivoted to bracket 96 and which is urged to the right, as viewed in Fig. 1, by a spring 99. Lever 98 has two notches, one arranged to hold the arm 97 in a horizontal plane with respect to the movement of tape 50, and the other serving to hold the arm 97 in a tilted or latched position. Cooperating with lever 98 are contacts 100 which are included, through a manually operable switch 101, in circuit through the upper armature and back contact of a relay 102 with the winding of electromagnet 102.

Under operating conditions, electromagnet 102 is normally energized and has its locking circuit controlled by contacts 100. When the tape 50 becomes taut, arm 97 is rotated in a counterclockwise direction and thus allows lever 98 to move to the right, as viewed in Fig. 1, under the action of spring 99. In so moving, lever 98 opens contacts 100 through which the locking circuit of relay 102 is interrupted. Due to the notch arrangement of lever 98, arm 97 is retained in the position to which it was moved by the action of tape 50, where it remains until lever 98 is

restored manually to the position shown in Fig. 1.

The receiving printer, represented diagrammatically in Figs. 3 to 6 and with which the transmitting apparatus exemplified by Figs. 1 and 2 cooperates, is normally operative, with its printing or recording wheel constantly rotating. However, the recording medium or tape is normally arrested during cessation of message transmission and reception, but upon receipt of the start condition controlled by code discs 19 or 20, as will presently appear, the tape movement is initiated and continues without the exercise of further control from discs 19 or 20.

Normally, with characters like B, D, H, N, etc., which begin with a vertical stroke, indicative of a prolonged marking condition, the movement of the tape would be initiated automatically upon resumption of message transmission, but with characters like C, G, O, S, V, etc., which do not begin with a vertical stroke, the tape control mechanism at the receiving end, which responds to a long marking impulse for initiation of message transmission, will not, when one of the last noted characters is the first character to be received upon resumption of message transmission, respond at the proper time to effect initiation of the movement of the tape due to the absence of a long marking impulse. To supply this long impulse invariably upon the resumption of message transmission, the code discs 19 and 20 are provided and are selected for operation in the following manner.

The starting condition is established through closure of switch 101 and 100 concurrently. Upon the closure of the switches, a circuit is established extending from grounded battery, through the closed contacts 100, the contacts of switch 101, the upper armature and back contact of de-energized relay 102 and the winding of selector electromagnet 36 to ground. Selector magnet 36 is thereupon energized and acts through a bell crank 42 to unlatch the permutation bar 30 which, in turn, is actuated by its spring 43 to its leftward position to produce a setting of the permutation bars to permit the selection of a selectable bar 63 identified with brush carrier 105 (Fig. 2) which, upon being operated and held in its operated position by ball 71, causes its brushes to engage contact discs 19 and 20. The periphery of these contact discs is formed such as to effect the transmission of a prolonged marking signal which functions as a start signal, the circuit of which may be traced from grounded battery connected to brush support 105, through either disc 19 or 20 (depending upon the position of contactor 88), springs 17 or 18, collector ring 15 or 16 (depending upon whether contactor 88 is in engagement with contacts 86 or 87), to the input side of the radio frequency transmitter 95. With regard to discs 19 and 20, it is noted that either of these discs may be effective for the transmission of a start impulse, regardless of whether the transmitting apparatus was previously employed for the transmission of either letters or figures combinations. Consequently, regardless of the previous position of contactor 88, a start impulse will be transmitted in response to manual closure of switches 100 and 101.

Operated upon the selection and operation of brush carrier 105 are contacts 106. These contacts are connected to the winding of relay 102 and upon their closure, cause the energization of relay 102 over a circuit extending from grounded battery through contacts 106, con-

ductor 107, and the winding of relay 102 to ground. Relay 102, upon being energized, establishes its locking circuit extending from grounded battery through contacts 100 now closed, contacts of switch 101, armature and front contact and winding of relay 102 to ground. Relay 102 thus is maintained energized as long as contacts 100 and the contacts of switch 101 are closed. The closure of contacts 106 is momentary. Contacts 106 open when brush 105 drops out of selection due to the change in the setting of code bars 63 brought about by opening the upper contact of relay 102 when relay 102 is energized upon closure of contact 106. Selector magnet 36 is thereafter under the control of the tape sensing mechanism.

Upon the energization of relay 102, an energizing circuit for relay 108 is conditioned which will be completed upon the closure of contacts 109 under the control of cam 25. As previously described, cam 25 is effective cyclically with respect to the other cams secured to shaft 1 and the code signal discs 12 also secured to shaft 1, so that for each cycle of rotation of shaft 1, contacts 109 will be closed and with relay 102 energized, an energizing circuit will be completed for relay 108 extending from grounded battery, through contacts 109, conductor 110, conductor 111, lower front contact and armature of relay 102, and the winding of relay 108 to ground. Relay 108 is thereupon energized and opens, through its back contact and armature, a locking circuit for relay 112 which has its right-hand winding connected in series with the windings of electromagnet 58 and which will thus be energized upon the completion of an energizing circuit including the right-hand winding of relay 112.

Also connected in circuit with contacts 109 are the windings of electromagnet 52. Therefore, upon the cyclic closure of contacts 109, a circuit will be completed for the energization of electromagnet 52 which extends from grounded battery, through contacts 109, conductor 110, conductor 111, conductor 113, and the winding of electromagnet 52 to ground. Electromagnet 52 will thereupon be energized for causing the retraction of tape feelers 46 and the advancement of tape 50 to present the succeeding transverse row of perforations in alignment with the tape feelers 46.

The left-hand winding of relay 112 is also controlled by contacts 109 and is energized momentarily upon the closure of such contacts to close the circuit including its right-hand winding and the windings of electromagnet 58. However, with relay 108 also energized, due to the fact that relay 102 is now energized, an energizing circuit for the windings of electromagnet 58 is not completed.

Assume, for the purpose of illustration, that tape 50 becomes taut and further, that arm 97 is operated to permit spring 99 to move lever 98 sufficiently to open contacts 100. Contacts 100 control, as previously described, the locking circuit for relay 102. Consequently, upon the opening of contacts 100, relay 102 is de-energized and opens, through its lower armature, the circuit for relay 108. Now, upon the next closure of contacts 109, relay 108 will not be energized and its back contact will be closed so that upon the energization of the left-hand winding of relay 112, an energizing circuit for its right-hand winding or locking winding is completed

extending from grounded battery, conductor 114, back contact and armature of relay 108, armature and front contact of relay 112, right-hand winding of relay 112, conductor 115, and the windings of electromagnet 58 to ground. Due to the establishment of such a circuit, relay 112 will be maintained energized and electromagnet 58 will be energized to hold, through its armature 59, the pivoted plate 57 of electromagnet 52 to hold the tape feelers 46 out of engagement with tape 50 and prevent the further advancement of the tape. Transmission under such conditions will be arrested. It is, of course, understood that the shaft 7 and its code discs, together with its cams, continues to rotate. Contacts 109 will be closed cyclically through the operation of cam 25 and current will be impressed upon the windings of electromagnet 52, but its energization will have no effect since electromagnet 58 is energized and the pivoted plate 57 is rendered ineffective.

To start transmission, notwithstanding the fact that tape 50 may have in the meantime become slack and a loop formed therein, it is necessary for an operator to restore manually lever 98 to the position shown in Fig. 1. Upon such restoration, contacts 100 will be closed and a circuit will be established for electromagnet 38 through the energization of which, as previously described, brush support 105 will be selected and operated for the transmission through discs 19 and 20 of a start impulse, contacts 106 will be closed, and an energizing circuit for relay 102 will be established.

When transmission of all messages has been completed, switch 101 may be opened and the result described for the opening of contacts 100 will be effected.

The signals transmitted from the radio frequency transmitter 95 (Fig. 2) are received by the radio frequency receiver 120 (Fig. 3), where they are demodulated and amplified and are directed through a line coil 121 of a radio printing apparatus of the type shown in aforementioned Patent No. 2,131,741, thence to ground. These signals are also directed over conductor 122, through winding 123 of a double winding relay 124, and thence to the ground. The line coil 121 and the winding 123 are, accordingly, connected in parallel. The radio printer disclosed schematically in Fig. 3 comprises the printing or recording wheel 125 which is normally rotating constantly. As disclosed in said copending application, printing or platen wheel 125 is provided on its cylindrical surface with symmetrical spiral knife edges 126 which cooperate with an operating member or platen 127, having a knife edge arranged transversely of the tape 128. Platen 127 moves with the line coil member 121 and reciprocates vertically with the line coil in response to the received signals. Thus, in response to a marking signal the line coil will be actuated upwardly, bringing the platen against the printing wheel, then upon receipt of a spacing signal the coil moves downwardly under the action of gravity or by means of a return spring, bringing the platen against a down stop 221 (Fig. 8.) To prevent bouncing of the platen which occurs when the platen is rigidly secured to the line coil spool 222, thus causing undesirable marks on the tape, especially when an inking roller is used, the construction shown in Fig. 8 is employed. With this arrangement, the platen 223 is fitted into a bushing 224 supported by the line coil spool 222. The spool 222 is in-

terposed between a pair of rubber washers 225, preferably of sponge rubber, which are clamped between a flange on the platen 223, and a metal washer 226, by a cotter pin 227. The rubber washers act to eliminate rebound because of the ability of rubber to absorb mechanical energy without releasing the same due to its high internal friction. Thus, when the assembled platen and line coil are actuated upwardly toward the printing wheel in response to a marking signal, the platen 223 strikes the printing wheel and tends to rebound, but due to the continued upward force of the line coil spool 222 the rebound of the platen is resisted, the rubber washers 225 serving to absorb the mechanical energy expended by both the platen and the line coil. The same result is achieved upon the return or downward movement of the assembled platen and line coil when the platen 223 impinges against the down stop 221. With this arrangement distinct printing is assured. Obviously, any material having high internal friction might be used in place of rubber.

The line coil 121 is arranged over the core 129 of the local field magnet 131 and operates between the poles 132. The winding of the coil 121 is connected in an obvious circuit, such as is diagrammatically shown in Fig. 3. As fully described in the aforementioned Patent No. 2,183,741, the field coil 121 responds to marking signals to raise the platen 127 against the tape 128, thus pressing the tape 128 and a contiguous strip of carbon paper against the spiral knife edges 126 of the rotating printing wheel 125, whereby the tape 128 is marked in accordance with the received marking signals to record characters. It is understood, of course, that an ink roller may be substituted for carbon paper. As contemplated by the present invention, the tape 128 moves only during signal reception and for a predetermined interval thereafter, and control means is provided to stop the tape after said predetermined cessation of message reception. For example, tape feeding continues for at least twenty-five character spaces after transmission and reception have ceased.

As previously mentioned, the signal impulses extend over conductor 122 through the winding 123 of the double winding relay 124. During signal reception, the received marking impulses cause the relay 124 to become energized. Upon energization, relay 124 attracts its armature 133 to close contact 134, thereby establishing a locking circuit from positive battery, through a second winding 135 of relay 124, through contact 134 (now closed), armature 133, thence through the windings of a stop magnet 136, through a contact 137, to ground. When this circuit is established, magnet 136 becomes energized and pulls up its armature 138. Armature 138 is provided with a stop lug 139 which cooperates with a projection 141 on the periphery of a stop disc 142 connected to a shaft 143 by means of a friction clutch (not shown).

Accordingly, in response to the first marking signal the double winding relay 124 will be energized to establish the energizing circuit above-described for the stop magnet 136, which by attracting its armature 138 permits rotation of the stop disc 142 to be initiated. The stop disc 142 being operatively associated with the tape feed roller 144, thereby controls the initiation of movement of the tape 128.

As previously mentioned, to assure that the characters are properly recorded, a special start-

ing impulse is transmitted upon the resumption of message transmission, so that when the character signals are received by the radio printer, the tape 128 will have been started in motion by the operation of magnet 136. The starting condition, being invariably supplied by the operation of code discs 19 and 20, always acts to initiate the movement of the tape, which moves continually thereafter so long as character signals are being received.

The projection 141, after being released by the armature 138, operates, after traveling a few degrees, to open the contact 137 to break the locking circuit previously described for magnet 136 and relay 124. In response to this condition, armature 133 is released and contact 134 is opened. Also, armature 138 is released to bring lug 139 thereon again into the path of the projection 141 of disc 142. A time interval corresponding to about twenty-five characters is required for the tape driving disc to reach the stop position after opening the contact 137; therefore, if there should occur a cessation of message reception longer than this interval, the movement of the tape 128 will be automatically arrested.

A modified form of automatic tape control is shown in Fig. 4. This arrangement is similar to the one shown in Fig. 3, the received impulses entering over the conductor 151 and dividing at 152 to pass through the line coil 153 and winding 154 of a double winding relay 155, the coil 153 and the winding 154 being connected in parallel. Like the arrangement in Fig. 3, the coil 153 and winding 154 respond to the marking impulses. The line coil 153 cooperates with the local field coil 156 to actuate platen 157 against the recording wheel 158 in the manner previously described in connection with Fig. 3. A start impulse will energize the winding 154 to attract the armature 159 to close the contact 161 to complete an energizing circuit for magnet 162 from battery, through winding 163 of relay 155 over armature 159, through contact 161, through the winding of magnet 162, through the closed contact 164 to negative battery. The latter described circuit comprises a locking circuit for both the relay 155 and the magnet 162. Magnet 162 upon being energized attracts its armature 165 to release the stop disc 166 for rotation. Stop disc 166 after rotating a few degrees acts to open the contact 164 to break the locking circuit for magnet 162 and relay 155, in the manner described in connection with Fig. 3. Therefore, if a marking signal is received at or before the time that the disc 166 is about to be stopped by the armature 165, the armature 165 will be actuated out of the path of disc 166 to permit it to continue its rotation, thereby, in this manner imparting continuous movement to tape 167.

Another form of automatic tape control at the receiver is shown in Fig. 5. In this arrangement, the amplified signals enter at 171 and extend through the line coil 172 to ground. The line coil acts in conjunction with the local field magnet 173 to reciprocate the platen 174 into operative engagement with the recording wheel 175 fixed to the shaft 176. Connected to the shaft 176, by means of a friction clutch, is a stop disc 177. In the arrangement shown in Fig. 5, the movement of the tape is controlled directly and mechanically by the line coil structure 172. Line coil 172, during its vertical reciprocation, acts through a stud 178 to rock a bell crank latch member 179 which is biased by a spring 181 in a counterclockwise direction (as viewed in Fig. 5).

Latch 179 cooperates with one arm of a three armed lever 182. Arm 183 of lever 182 cooperates with the projection portion of disc 171, to hold the disc 177 against rotation in a counterclockwise direction. Line coil 172 in response to a marking signal rises to bring the platen 174 into cooperation with the recording wheel 175 and, in so doing, actuates through stud 178, the bell crank 179 clockwise against the action of its spring 181, thereby unlatching the lever 182, which responds to the pull of its spring 184 to disengage arm 183 from the disc 177, thus permitting rotation of the disc 177, which controls through an obvious gear train, the initiation of the movement of the printing tape 170. As the lever 182 is actuated by the spring 184, its arm 185 is brought against the periphery of the disc 177, and after the disc 177 has rotated a few degrees, its projection acts upon the arm 185 to rotate the lever 182 in a clockwise direction against the action of its spring 184 to restore the lever 182 into latching engagement with the latch lever 179, thereby bringing the arm 183 into the path of the projection on disc 177. If at or before the time the projection on disc 177 reaches the arm 183, a marking signal is impressed on the winding of line coil 172, the lever 182 will again become disengaged from the disc 177, or rather held out of operative engagement with disc 177 to permit the continuous rotation of disc 177 and the associated tape feed rollers to impart continuous movement to the tape.

In the form of the invention shown in Fig. 6, an arrangement is shown in which a gas filled 35 electronic tube is substituted for the double winding relays 123 and 155, in Figs. 3 and 4, respectively. The tube used is of the trigger type, in which, if the grid becomes sufficiently positive with respect to the cathode, plate current will begin to flow and will thereafter be independent of grid voltage. The flow of current in this type of tube can only be stopped by opening the plate circuit (or otherwise reducing the plate voltage). Referring to Fig. 6, 40 the signals are directed over the conductor 191, then through the line coil 192 to ground. The grid 193 of electronic tube 194 is connected in parallel with the line coil 192. The plate 195 of the tube 194 is connected to the winding of a magnet 196. The circuit for magnet 196 extends from battery 197 through the tube 194, thence through the winding of magnet 196, over conductor 198, through contact 199, then back to battery 197. Accordingly, when marking signals 45 are received over the line 191, the line coil 192 will be actuated upwardly to effect printing, and since the flow of current through the printing coil causes a voltage drop across the line coil 192, thus voltage is impressed across the tube grid and cathode which are connected in parallel with the line coil 192, thus tripping the tube and allowing plate current to flow continuously thereafter through the circuit previously described for the magnet 196, causing magnet 196 to become energized until interrupted by opening of contact 199. Upon energization, magnet 196 will attract its armature lever 201, to effect the disengagement of lever 201 from the disc 202 to impart, through shaft 203 and tape feeding rollers (not shown), movement to tape 204. After the disc 202 has been initiated into rotation and rotated a few degrees, a pin 205 thereon acts to open the contact 199. The opening of contact 199 breaks the circuit for magnet 196, whereupon lever 201

is again released to be presented in the path of the stop projection on disc 202, and in like manner to the arrangements previously described continuous movement will be imparted to the tape 204 unless a spacing condition exists from reclosing of 199 until the projection on 202 reaches the armature lever 201.

The present invention also provides, as shown in Fig. 7, a means for printing or marking on a sensitized or chemically prepared tape, such as a wax coated tape, by means of sparking or arcing from a free running spiral member 215 near the tape 216 but out of contact. With this arrangement, signals are transmitted from the transmitter over the conductor 206, through the contact 207, through the primary winding 208 of transformer 209, over conductor 211, to negative battery. Transformer 209, in the present embodiment, is shown as a step-up transformer with an interrupter or vibrator in the primary. The vibrations caused in the vibrator of transformer 209 generate higher voltage in the circuit including the secondary winding 212, the contact 213 and 214, and the recording wheel 215. High voltage is necessary to break down the resistance of the air gaps between the knife edges and scanning wheel 215. The arcing or sparking thus produced between the contact 214 and the recording wheel 215, causes a record to be made or impressed on the chemically prepared tape 216 interposed between the contact 214 and the wheel 215, without requiring pressure as in the structures of Figs. 3, 4, and 5, and requiring a minimum of power to rotate the spiral printing member.

While the invention has been described and disclosed with regard to a particular type of apparatus, it is manifest that various departures may be made from the disclosure without departing from the spirit and scope of the invention.

What is claimed is:

1. In a telegraph system, a transmitting element and a receiving element rotatable synchronously, record reading means for controlling signal transmission, receiver tape feeding means, means for stopping said tape feeding means automatically upon cessation of signal transmission, and means effective independently of said record reading means for inserting a start signal invariably upon the resumption of signal transmission to insure that tape feeding starts in the receiver when the transmitter is started.

2. In a telegraph system, a signal channel, a record reader, means operable under the control of said record reader for transmitting over said signal channel groups of signals in successive cycles, each cycle corresponding to the light and dark areas of a scanned character, means effective independently of said record reader for transmitting over said signal channel a tape start condition, in combination with a receiver connected to said channel and provided with a printing mechanism responsive to received signals over said channel to record the transmitted character, tape feeding mechanism at said receiver, and means responsive to said start condition to control said tape feeding mechanism.

3. In a telegraph system, a record reader for controlling the transmission of a series of individual symbols, physical embodiments of each of said symbols, a signal channel, a signal generating scanning device connected to said channel, means controlled by said record reader to

operatively associate any one of said embodiments of symbols with said scanning device, certain of said embodiments effective independently of said record reader to transmit a control impulse, a recording device connected to said channel, and means in said recording device effective under the control of said control impulse for controlling the movement of a recording medium through said recording device.

4. In a telegraph system, a signal channel, a series of character members, a scanning device connected to said channel, means controlled by a record tape to operatively associate any character member with said scanning device, electrical circuit means effective under certain operating conditions to initiate the operation of said scanning device, and means controlled by said circuit means to automatically prevent the operation of the scanning device when the tape has become taut.

5. In a telegraph system, a signal channel, a series of character members, a scanning device connected to said channel, means effective under the control of a controlling medium to operatively associate any character member with said scanning device, electrical circuit means effective under certain operating conditions to initiate the operation of said scanning device, and means controlled by said circuit means to automatically prevent the operation of the scanning device when said medium becomes taut.

6. In a telegraph system, a signal channel, a series of character members, a scanning device connected to said channel, means effective in response to a control strip to operatively associate any character member with said scanning device, a recording device responsive to said association, electrical circuit means effective under certain operating conditions to start said scanning device into operation, means responsive to said scanning device under the control of said strip to control a recording medium in said recording device, and means controlled by said circuit means to automatically prevent the operation of both said devices when said control strip becomes taut.

7. In a telegraph system, a signal channel, a series of constantly rotatable symbols, a scanning device, sensing means controlled by a record tape for controlling the scanning of any one of said symbols by said device, electrical circuit means effective under certain operating conditions for initiating operation of said tape sensing means, and means controlled by said circuit means to automatically prevent the operation of said tape sensing means in response to a taut condition of the tape.

8. In a telegraph system, a signal channel, means to transmit over said channel a group of signals individual to each character which are composed of a plurality of scanning lines, means to transmit a single starting signal preceding each series of groups of character signals, a recorder, normally inert tape feed mechanism at said recorder, and means controlled by a signal generated by said second recited means to initiate the operation of said tape feed mechanism.

9. In a telegraph system, a tape controlled transmitter, a transmitter controlling circuit, a manually operable lever having an operating position, a spring attached to said lever and urging said lever from its operating position, a switch in said circuit and closed by said manual

lever when in operating position, and a latch engaging said lever and restraining said lever in operating position, said latch responsive to the tape in taut condition to unlatch said lever to interrupt said circuit to stop said transmitter.

10. In a telegraph system, a tape controlled transmitter, a lever effective to start said transmitter into operation upon manual operation, and a latch engaging said lever and effective to restrain said lever in operated position to maintain said transmitter in operation, said latch responsive to the tape becoming taut to release said lever to stop said transmitter.

11. In a telegraph system, a tape controlled transmitter, manual means to start said transmitter, a latch for said manual means, and tape controlled means to operate said latch to unlatch said manual means.

12. In a printing telegraph system, a tape-driving mechanism, starting means for said tape-driving mechanism, including a self-holding circuit, a circuit including a winding of a relay responsive to a line signal for closing said self-holding circuit, and means operable by said tape-driving means after leaving stop position for interrupting said self-holding circuit.

13. In a printing telegraph system, a tape-driving mechanism, trigger means responsive to a line signal for starting said tape-driving mechanism, and means operable by said tape-driving means after leaving stop position for resetting said trigger means.

14. In a printing telegraph system, a tape-driving mechanism, trigger means including a gas filled electronic trigger valve responsive to a line signal for starting said tape-driving mechanism, and means operable by said tape-driving means after leaving stop position for resetting said trigger means.

15. In a printing telegraph system, a plurality of transmitting elements representing severally the several characters to be transmitted, an additional transmitting element, a manual switch, means responsive to said manual switch to qualify said additional transmitting element to transmit a control signal, and further means responsive to said first mentioned means to qualify subsequently ones of said first mentioned transmitting elements to transmit printing signals.

16. A telegraph transmitter including a mechanism for sensing control indicia on a control strip, a plurality of transmitting elements each having a series of spaced contact segments representative of light and dark areas of a scanned character, means cooperative with said elements for transmission of corresponding impulses, a plurality of permutation bars, means controlled by said permutation bars for controlling the se-

lection and operation of said cooperative means, means controlled by the indicia sensing mechanism for setting said permutation bars in varying combinations to select the cooperative means, and means responsive to a condition of the control strip for precluding the operation of said indicia sensing mechanism.

17. A telegraph transmitter including a mechanism for sensing control indicia on a control strip, a plurality of transmitting elements each having a series of spaced contact segments representative of light and dark areas of a scanned character, means cooperative with said elements for transmission of corresponding impulses, a plurality of permutation bars, means controlled by said permutation bars for controlling the selection and operation of said cooperative means, means controlled by the indicia sensing mechanism for setting said permutation bars in varying combinations to select the cooperative means, mean responsive to a condition of the control strip for precluding the operation of said indicia sensing mechanism, and manually operative means effective following the operation of said last-mentioned means for establishing a condition whereby said indicial sensing mechanism may be operated and to operate one of said permutation bars to control the transmission of a start signal.

18. A telegraph transmitter including mechanism for sensing control indicia on a control strip, a plurality of transmitting elements one identified with each element of a permutation code, means cooperative with said elements for transmission of corresponding impulses, an electromagnet in said indicia sensing mechanism, and means responsive to a condition of the control strip for energizing said electromagnet to preclude the operation of the indicia sensing mechanism.

19. A telegraph transmitter including mechanism for sensing control indicia on a control strip, a plurality of transmitting elements one identified with each element of a permutation code, means cooperative with said elements for transmission of corresponding impulses, an electromagnet in said indicia sensing mechanism, means responsive to a condition of the control strip for energizing said electromagnet to preclude the operation of the indicia sensing mechanism, and manually operative means effective following the operation of said last-mentioned means for establishing a condition whereby said electromagnet is de-energized and said indicia sensing mechanism may be operated under the control of said control strip.

RAYMOND E. ZENNER.
